UNITED STATES PATENT OFFICE.

HARRY KAUFMAN AND FRANK M. KAUFMAN, OF PHILADELPHIA, PENNSYLVANIA,
ASSIGNORS TO FRED PEARSON & COMPANY, INC., OF PHILADELPHIA, PENNSYLVANIA, A CORPORATION OF PENNSYLVANIA.

WOVEN PILE FABRIC.

1,249,768.

Specification of Letters Patent. Patented Dec. 11, 1917.

Application filed March 1, 1917. Serial No. 151,738.

To all whom it may concern:

Be it known that we, HARRY KAUFMAN and FRANK M. KAUFMAN, citizens of the United States, residing at Philadelphia, county of Philadelphia, and State of Pennsylvania, have invented certain new and useful Improvements in Woven Pile Fabrics, of which the following is a specification.

Our invention relates to improvements in woven pile fabrics, the object of the invention being to provide a cut pile fabric, in which the warp pile threads which form the tufts of the fabric are firmly secured in the backing, and are so uniformly positioned as to present a smooth surface.

A further object is to provide a woven pile fabric in which the tufts are formed by warp pile threads in banks of six, each bank divided into two series of three pile threads, and with the alternate pile threads in any series extending in the same direction from one backing fabric to the other, and the adjacent pile threads extending in opposite directions, and the corresponding pile threads of the adjacent series oppositely positioned.

A further object is to improve upon the fabric disclosed in Patent No. 1,169,835, granted to us February 17th, 1916.

With these and other objects in view the invention consists in certain novel features of construction and combinations and arrangements of parts as will be more fully hereinafter described and pointed out in the claims.

In the accompanying drawings:

Figure 1 is an exaggerated view in longitudinal section, illustrating our improved pile fabric.

Figs. 2, 3, 4, 5, 6, and 7 are views similar to Fig. 1, each view showing but one pile thread connecting the backing fabric, and

Fig. 8 is a diagrammatical plan view of the fabric X after the pile is cut.

Our improved fabric consists of top and bottom backing fabrics X and Y respectively, which are connected by warp pile threads, 1, 2, 3, and 1^a, 2^a, and 3^a respectively. These reference characters are used to indicate that the pile threads are formed in banks of six threads each, each bank divided into two series of three threads each, with the threads of each series in the same bank oppositely disposed, as will be more fully hereinafter explained.

We would have it understood that we mean by the term "series of three threads" to refer to a group of three pile threads, which are successively placed transversely of the fabric and are separated, or set off from the other threads by a binding warp thread.

The top backing fabric X consists of binding warp threads 6 and 7, and weft threads A, B, C, D, E, and F, woven between the binding warp threads 6 and 7. The lower backing fabric Y consists of binding warp threads 4 and 5 with weft threads A', B', C', D', E' and F' woven therein.

The upper and lower picks of the weft threads are simultaneously woven by the shuttles, and hence for convenience of description, these pairs of picks of the weft threads are given corresponding letters, the reference letters of the picks of the bottom fabric being primed as described.

While Fig. 1 illustrates two binding warp threads in both upper and lower fabrics, it is to be understood that but a single binding warp thread is located between each series of three warp pile threads as indicated most clearly in Figs. 2, 3, 4, 5, 6 and 7 respectively.

Describing each of the warp pile threads of the bank of six, attention is called first to Fig. 2 which indicates the position of pile thread 1.

This thread passes first over weft thread A of the upper backing fabric X, and thence under weft thread B, and over weft thread C, thence downwardly under weft thread D', over weft thread E', and under weft thread F' of the lower backing fabric Y.

As shown in Fig. 3, pile thread 2 is positioned over weft thread A, thence down under weft thread B', over weft thread C', under weft thread D', thence up to and over weft thread E and under weft thread F.

Fig. 4 shows the position of pile thread 3 which passes first over weft thread A', thence under weft thread B', thence up to and over weft thread C, under weft thread D, over weft thread E, and thence down to and under weft thread F'.

Figs. 5, 6 and 7 show the positions of pile threads 1^a, 2^a, and 3^a, which it will be noted are directly opposed to the positions or locations of the pile threads 1, 2 and 3.

Tracing out these pile threads 1^a, 2^a and 3^a, we find in Fig. 5, that pile thread 1^a first passes under weft thread A', thence over

weft thread B', thence under weft thread C', thence up to an over weft thread D, under weft thread E, and over weft thread F.

5 By reference to Fig. 6, it will be seen that pile thread 2^a first passes under weft thread A', thence up to and over weft thread B, thence under weft thread C, thence over weft thread D, thence down to and 10 under weft thread E', thence over weft thread F'.

By reference to Fig. 7, we trace pile thread 3^a as beginning under weft thread A, thence over weft thread B, thence down 15 to and over weft thread C', thence over weft thread D', thence under weft thread E', thence up to and over weft thread F.

Having now traced the several threads of the pile, attention is directed to Fig. 1, which 20 shows on an exaggerated scale, the locations of all of these threads, and it will be noted in this figure, (due to the fact that the pile threads of each series of three are oppositely disposed) that the corresponding threads of 25 each series cross each other, but are woven in opposite directions as indicated by the arrow. When the fabric is cut along a center line between the two backing fabrics, the tufts will have a smooth appearance, 30 and all threads will be uniformly tied in the backing fabrics.

Various slight changes might be made in the general form and arrangement of parts described without departing from our invention, and hence we do not limit ourselves to the precise details set forth, but consider ourselves at liberty to make such changes and alterations as fairly fall within the spirit and scope of the appended claims.

40 Having fully described our invention what we claim as new and desire to secure by Letters Patent is:

1. A pile fabric, comprising top and bottom backing fabrics, a bank of pile threads 45 connecting the backing fabrics, each bank consisting of two series of three threads each, the threads of each series successively placed transversely of the fabric and separated or set off from the other threads by a binding 50 warp thread, the corresponding threads of each series oppositely disposed, and crossing each other at a point between the backing fabrics.

2. A pile fabric, comprising top and bottom 55 backing fabrics, a bank of pile threads connecting the backing fabrics, each bank consisting of two series of three threads each, the threads of each series successively placed transversely of the fabric and separated or 60 set off from the other threads by a binding warp thread, the corresponding threads of each series oppositely disposed and crossing

each other at a point between the backing fabrics, and the adjacent pile threads of each series extending in opposite directions from 65 one backing fabric to the other, while the alternate threads of each series extend in the same direction from one backing fabric to the other.

3. A pile fabric, comprising top and 70 bottom backing fabrics, a bank of pile threads connecting the backing fabrics, each bank consisting of two series of three threads each, the threads of each series successively placed transversely of the fabric and separated or set off from the other threads by 75 a binding warp thread, the corresponding threads of each series oppositely disposed and crossing each other at a point between the backing fabrics, said backing fabrics 80 consisting of weft threads and binding warp threads, a filling shot or weft thread of each backing fabric located between each pair of pile threads, and said shots located in parallelism, one above the other, the said pile 85 threads in both top and bottom fabrics woven with three of said shots, and a single binding warp thread in each backing fabric between each series of three pile threads.

4. A pile fabric, comprising top and bottom backing fabrics, a bank of pile threads connecting the backing fabrics, each bank consisting of two series of three threads each, the threads of each series successively placed transversely of the fabric and separated or set off from the other threads by a binding warp thread thereof, the corresponding threads of each series oppositely disposed and crossing each other at a point between the backing fabrics, and the adjacent pile 90 threads of each series extending in opposite directions from one backing fabric to the other, while the alternate threads of each series extend in the same direction from one 95 backing fabric to the other, said backing fabrics consisting of weft threads and binding warp threads, a filling shot or weft thread of each backing fabric located between each pair of pile threads, and said shots located in parallelism, one above the other, the said pile threads in both top and bottom fabrics woven with three of said 100 shots, and a single binding warp thread in each backing fabric between each series of three pile threads.

In testimony whereof we have signed our names to this specification in the presence of two subscribing witnesses.
